UNITED STATES PATENT OFFICE.

EDWARD T. BURGESS, OF CORNING, NEW YORK.

DESIGN FOR GLASSWARE.

SPECIFICATION forming part of Design No. 13,043, dated July 18, 1882.

Application filed May 13, 1882. Term of patent 7 years.

To all whom it may concern:

Be it known that I, EDWARD T. BURGESS, of the village of Corning, in the county of Steuben and State of New York, have invented 5 a new and original Design to be Cut into or upon Glassware for the purpose of ornamenting the same; and I do hereby declare that the following is a full and clear description of the same, reference being had to the annexed 10 drawing, (Patent Office No. 61,197,) which makes a part of this description and specification.

This design is a combination of diamonds, hexagons, and stars formed by a series of parallel miter cuts into the surface of the glass- 15

ware, said figures being brought to a point or left with flat surfaces, according to the depth of the cut. The miter cuts or grooves are designated in the annexed drawing by lines A A, B B, and C C, cut or running across the surface at the respective angles of 58°, 0°, and 90°, so as to form said figures, as shown. 20

I claim—

The miter cuts or grooves A A, B B, and C C, in their relative positions forming the stars, 25 hexagons, and diamonds, as shown.

EDWARD T. BURGESS.
